(57) **CLAIM**

The ornamental design for a base of a blender, as shown and described.

DESCRIPTION

FIG. 1 is a top, front, right side perspective view of a base of a blender showing our new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof, the left side being a mirror image of FIG. 6.

The portions of the base of a blender shown in dotted lines are not part of the claimed invention.
